UNITED STATES PATENT OFFICE.

CARL J. CARLSON, OF BLUE ISLAND, ILLINOIS.

DESIGN FOR A COMBINED SHOE HORN AND BUTTONER.

41,298.

Specification for Design.

Patented Apr. 11, 1911.

Application filed February 6, 1911. Serial No. 607,002. Term of patent 7 years.

To all whom it may concern:

Be it known that I, CARL J. CARLSON, a citizen of the United States, residing at Blue Island, in the county of Cook and State of Illinois, have invented a new, original, and ornamental Design for a Combined Shoe Horn and Buttoner, of which the following is a specification, reference being had to the accompanying drawing, forming a part thereof.

The figure is a plan view of a combined shoe horn and buttoner showing my new design.

I claim—

The ornamental design for a combined shoe horn and buttoner as shown.

CARL J. CARLSON.
